UNITED STATES PATENT OFFICE.

HENRY R. GILSON, OF BADEN, PENNSYLVANIA.

METRIC VALVE.

1,227,607.

Specification of Letters Patent.

Patented May 29, 1917.

Application filed August 31, 1914. Serial No. 859,449.

To all whom it may concern:

Be it known that I, HENRY R. GILSON, residing at Baden, in the county of Beaver and State of Pennsylvania, a citizen of the United States, have invented or discovered certain new and useful Improvements in Metric Valves, of which improvement the following is a specification.

My invention relates to metric valves, and the object thereof is, in addition to improving the general construction, operation and efficiency of such valves, to provide a durable and practical valve that may be set in operation with minimum effort.

In the accompanying sheet of drawings, forming part of my specification, I have illustrated one embodiment of my invention. Figure 1 is a sectional view taken on the line I—I, Fig. 2; Fig. 2 a sectional view taken on the line II—II, Fig. 1; Fig. 3 a sectional view taken on the line III—III, Fig. 2; and Fig. 4 a detached detail view showing the arrangement of gears. The relative positions of the several elements constituting the complete valve structure are the same in Figs. 1, 2 and 4, while in Fig. 3 a different position is shown in full lines and still another position in dotted lines, as will be explained hereinafter.

Like numerals are used to designate like parts in the several figures.

While my invention may be employed in metric valves adapted to be used for various specific purposes, it is particularly applicable to valves for supplying a predetermined quantity of water for flushing water closets. It is desirable in metric valves for this purpose that, commensurate with structural durability and efficiency, they be compact in form; that there shall be no uncertainty of their action; that their operation be easily effected; that they cannot be held open to waste water; and that, without requiring external adjustment, the same amount of water will be delivered during each operation regardless of the supply pressure. Furthermore, when used with siphon closet structures it is desirable, in order to prevent the siphon action of the closet from drawing too much water from the bowl, to so construct the valve as to retard or diminish the final flow of water to the bowl. Finally, it is desirable that there be no hammering action as the valve closes. It is toward these features of metric valve construction that my invention is primarily directed.

Referring to the drawing, the valve structure and operating mechanism is mounted in a casing 1, preferably made of cast brass, and having a lateral inlet 2 and an outlet 3. The inlet leads to an inlet chamber 4 which is separated from an outlet chamber 5 by a partition 6 having a valve orifice 7 through it. The valve for closing the orifice 7 may be of any desired or well known type, but preferably comprises a closure or valve 8, having a laterally projecting portion, provided with a gasket 9 which bears upon the annular upturned edge of the orifice wall, as shown particularly in Fig. 2. To the end that the valve 8 may be easily accessible for repair, the portion of the casing forming the inlet chamber is provided with an opening 10, adapted to be closed by a removable plug 11, through which opening the valve 8 may be removed after the fluid supply has been shut off at a point beyond the inlet 2.

In operating the valve to permit a predetermined quantity of water to flow through the orifice 7, means are provided to effect an initial unseating of the valve closure, the pressure and velocity of the water flowing through the partly opened valve being then effective to cause the operating mechanism to further unseat the closure and to subsequently seat it. And, to the end that the initial opening of the valve may be accomplished with a minimum effort on the part of the operator, the valve closure is preferably tilted or raised only at one side, rather than being raised bodily against the fluid pressure in the inlet chamber.

For the purpose of thus operating the valve, any suitable mechanism may be employed. In the illustrative embodiment of my invention the valve closure 8 is provided with a depending stem 12 having at its lower end a slot opening 13 adapted to receive a pin 14 secured eccentrically to a rotatable pinion 15. In the lowermost position of this pin, as indicated in Figs. 1 and 2, the valve is closed, while in Fig. 3 the valve is tilted, the pinion 15 having been turned through a small angle in a right handed direction as viewed therein. As will readily be seen, the slot opening 13 permits the closure 8 to be tipped on its seat before being lifted bodily therefrom. The further and complete revolution of the pinion causes the valve 8 to rise from, and to again rest upon the valve seat in a reverse manner to which it was opened, the stem 12 being pro-

vided with radially extending ribs 16 to properly guide the valve to its seat.

The means for effecting the initial unseating of the valve may be best explained 5 after having described the mechanism for effecting the further rotation of the pinion 15. The fluid, or a portion of it, after it passes through the orifice acts upon a fluid motor, preferably in the form of a paddle 10 wheel 18, secured to a rotatable shaft 19, and having blades 17. As seen particularly in Fig. 4, the shaft 19 is provided with a small pinion 20, which meshes with a pinion 21 secured to a rotatable shaft 22. The shaft 22 15 is in turn provided with a pinion 23 meshing with a pinion 24 rotatably mounted upon a shaft 25; and to the pinion 24 there is secured a pinion 26, which meshes with pinion 15 and is also rotatable upon the shaft 25. 20 By properly proportioning the size of the several pinions, the number of revolutions of the fluid motor 18 required to effect a single rotation of the pinion 15 may be varied so as to permit any desired quantity of fluid to 25 pass through the valve during one cycle of its operation.

The initial opening of the valve by a partial turning of the pinion 15 is preferably effected by means of a hand lever 27 secured 30 to the shaft 25, to which there is also secured an arm 28 having a pawl 29 at its outer end in such position as to engage, when the lever is turned in one direction, a tooth of a ratchet wheel 30 secured to the pinion 24 and rotatable upon the shaft 25. The lever 27 is held in the position indicated in full lines in Fig. 3 by means of a spring 31, the opposite ends of which engage the casing 1 and the shaft 25, to which 35 the lever is secured. By moving the lever 40 through an arc of about 90° the valve 8 and the stem 12 will be brought to the positions indicated in Fig. 3, and, because of the positive connection between the pinion 24 and the motor shaft 19, it will be understood 45 that the movement of the lever 27 will also rotate the fluid motor. By such an arrangement the rotation of the motor will have been started before fluid, passing through 50 the partially opened valve, impinges upon its blades, thus eliminating all uncertainty of the operation of the valve. After the initial opening of the valve the ratchet 30, being secured to the pinion 24, continues to 55 rotate with such pinion, the pawl 29 slipping over the teeth of the ratchet. Since, in effecting the initial opening of the valve, the movement of the lever is always in the same direction as that of the rotation of 60 the ratchet during the further opening and closing of the valve, it follows that the valve cannot be held open to waste water by holding the handle in any position after the initial opening of the valve. In other words, 65 after the initial opening of the valve, its

further complete cycle of operation is entirely under the control of the fluid motor regardless of the position of the operating lever.

As stated heretofore, either all or a portion of the fluid passing through the valve may be directed upon the blades of the fluid motor. However, to the end that the entire construction may be as compact as possible, the casing is, by means of a removable partition 39, divided into two chambers, one containing the motor and the other the train of operating pinions. Fluid from the valve orifice passes through both chambers, thus rendering it possible to reduce the motor to such proportions as are necessary only to assure the operation of the valve, and without sacrificing the quantity rate of flow through the valve. A further advantage in providing two compartments and in causing part of the water to flow through each of them is that the quantity of fluid delivered by each operation of the valve may be varied by increasing or diminishing the area of an inlet or outlet passage of one 90 of such chambers. For example, by decreasing the area of the outlet passage of the gear chamber a greater proportion of the fluid will pass through the paddle wheel chamber, with the result that a smaller 95 quantity of fluid will be delivered at each operation of the valve. Adjacent to the motor the casing 1 is provided with a removable closure 33 for the purpose of assembling the operating mechanism and to 100 gain convenient access thereto.

In the operation of the valve construction, the hand lever 27 is moved from its full to its dotted line position, as shown in Fig. 3, and, through the pawl 29 and ratchet 30, causes the entire train of mechanism to move through a portion of its cycle of operation, thereby tilting the valve closure 8 to the position indicated in full lines in Fig. 3 and setting the paddle wheel 18 in rotation. The fluid, passing through the partially opened valve, causes a continued rotation of the paddle wheel and the consequent further opening and closing of the valve, the wide open position being indicated in dotted lines in Fig. 3. When the valve is nearly closed, the water pressure acting on the top of the valve closure 8 and aided by the diminishing supply of water impinging on the motor blades, tends to drive the gear train through the stem 12 until the valve is closed. When the valve closure is seated the supply of fluid is shut off from the paddle wheel, which will then stop rotating. It will be observed that the supply of water is gradually, rather than suddenly, shut off. This has the double advantage of, first, preventing hammering, and secondly, when the valve is used for flushing siphon closets, the supply of water is gradually diminished. 130

the advantage of which has already been explained. It will further be observed that, with a relatively low supply pressure and consequent low velocity of entering water, the speed of rotation of the motor will be slower and the valve will be open longer than when a high pressure supply and therefore high velocity discharge is used, the quantity of water delivered at each operation of the valve in both cases being substantially the same.

I claim as my invention:

1. In a metric valve, the combination of a casing, a single valve therein for controlling flow therethrough, means for effecting an initial incomplete opening of said valve, and mechanically operable means for effecting a further opening and subsequent closing of said valve.

2. In a metric valve, the combination of a main valve, means for effecting an initial tilting thereof, and a mechanically operated means for effecting a further opening and subsequent closing of said valve.

3. In a metric valve, the combination of a main valve, manually operable means for effecting an initial incomplete opening thereof, and mechanically operable means impelled by fluid passing through said valve for effecting a further opening and subsequent closing thereof.

4. In a metric valve, the combination of a main valve comprising an orifice and a stem-provided closure seated thereon, a rotatable member operatively connected to said stem and adapted when passing through one revolution to positively open and close said valve, and means impelled by fluid passing through the valve for continuously rotating said member.

5. In a metric valve, the combination of a main valve comprising an orifice and a closure seated thereon, said closure having a stem secured to it, a rotatable member operatively connected to said stem and adapted when passing through one revolution to open and close said valve, manually operable means for effecting an initial rotation of said member, and fluid-impelled means for effecting a further complete rotation of said member.

6. In a metric valve, the combination of a main valve comprising an orifice and a

closure therefor, a paddle wheel adapted to be rotated by fluid passing through the orifice, means coöordinated with said wheel to open and close said closure, and means for effecting an initial opening of said closure and rotation of said wheel.

7. In a metric valve, the combination of a main valve comprising an orifice and a closure therefor, said closure having a stem secured to it, a rotatable member operatively connected to said stem and adapted when passing through one revolution to open and close said valve, a paddle wheel adapted to be rotated by fluid passing through said orifice, means coöordinated with said wheel for rotating said member, and means for effecting an initial rotation of said member and of said paddle wheel.

8. In a metric valve, the combination of a casing divided into inlet and outlet chambers, the outlet chamber being divided into compartments for a fluid motor and for valve operating mechanism, and a valve controlling communication between the inlet and outlet chambers, the fluid passing through said valve flowing partly through each of said compartments.

9. In a metric valve, the combination of a main valve comprising an orifice and a closure seated thereon, said closure having a stem secured to it, a rotatable member operably connected to said stem and adapted upon its rotation to open and close said valve, manually operable means for effecting an initial rotation of said member, and fluid-impelled means for effecting a further complete rotation of said member.

10. In a metric valve, the combination of a main valve comprising an orifice and a closure therefor, a paddle wheel rotatable by fluid passing through the orifice, means coöordinated with said wheel to move said closure from and toward said orifice, and means for setting in motion said coöordinated means for effecting an initial opening of said closure.

In testimony whereof I have hereunto set my hand.

HENRY R. GILSON.
